[57] CLAIM

The ornamental design for a multi-media storage and display unit, as shown and described.

DESCRIPTION

FIG. 1 is a rear and left side perspective view of a 2-tier embodiment of a multi-media storage and display unit showing our new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a rear and left side perspective view of a 3-tier embodiment of a multi-media storage and display unit showing our new design;

FIG. 7 is a front elevational view thereof;

FIG. 8 is a top plan view thereof;

FIG. 9 is a bottom plan view thereof;

FIG. 10 is a right side elevational view thereof;

FIG. 11 is a rear and left side perspective view of a 4-tier embodiment of a multi-media storage and display unit showing our new design;

FIG. 12 is a front elevational view thereof;

FIG. 13 is a top plan view thereof;

FIG. 14 is a bottom plan view thereof;

FIG. 15 is a right side elevational view thereof;

FIG. 16 is a rear and left side perspective view of a 5-tier embodiment of a multi-media storage and display unit showing our new design;

FIG. 17 is a front elevational view thereof;

FIG. 18 is a top plan view thereof;

FIG. 19 is a bottom plan view thereof; and,

FIG. 20 is a right side elevational view thereof.
